CLAIM

The ornamental design for a toilet paper holder with shelf, as shown and described.

DESCRIPTION

FIG. 1 is a perspective view of a toilet paper holder with shelf showing our design;

FIG. 2 is a front elevational view;

FIG. 3 is a rear elevational view;

FIG. 4 is a right side elevational view;

FIG. 5 is a left side elevational view;

FIG. 6 is a top perspective view; and,

FIG. 7 is a bottom perspective view.

The broken line disclosures in the view represents portions of the toilet paper holder with shelf in which the claimed design is embodied, but which forms no part of the claimed design.
